UNITED STATES PATENT OFFICE.

EDWARD L. MILES, OF STEVENS POINT, WISCONSIN, ASSIGNOR OF ONE-HALF TO LEVI E. GENETT, OF STEVENS POINT, WISCONSIN.

ANTISLIPPING ATTACHMENT FOR GANG-PLANKS.

1,329,057.

Specification of Letters Patent. Patented Jan. 27, 1920.

Application filed June 30, 1919. Serial No. 307,675.

To all whom it may concern:

Be it known that I, EDWARD L. MILES, a citizen of the United States, residing at Stevens Point, in the county of Portage, 5 State of Wisconsin, have invented certain new and useful Improvements in Antislipping Attachments for Gang-Planks; and I do hereby declare the following to be a full, clear, and exact description of the invention, 10 such as will enable others skilled in the art to which it appertains to make and use the same.

This invention relates to new and useful improvements in gang planks and particularly to attachments therefor.

The principal object of the present invention is to provide a novel and improved device for attachment to a gang plank which will prevent the gang plank from slipping 20 while in use.

Another object is to provide a novel and improved anti-slipping attachment for a gang plank which will also yield so as to permit the gang plank to lower and thus obviate a jolt to the truck as it passes onto or 25 off the gang plank.

Other objects and advantages will be apparent from the following description when taken in connection with the accompanying 30 drawing.

In the drawing:

Figure 1 is a side elevation of a gang plank equipped with my improved anti-slipping device.

Fig. 2 is an enlarged vertical sectional view taken on the line 2—2 of Fig. 1, through the anti-slipping device, the said device being in normal position.

Fig. 3 is a similar sectional view showing 40 the gang plank depressed under the load of a truck.

Fig. 4 is a top plan view of one corner of the gang plank showing the manner in which the anti-slipping device is secured thereto.

Referring particularly to the accompanying drawing, 10 represents a gang plank of the type in general use and which is formed of metal. This gang is usually formed of a single sheet of metal about three-eighths of 45 an inch thick with one end turned down, as shown at 11, and the other end tapered or beveled to a thickness of about one-eighth of an inch, as shown at 12. The beveled end 11

is placed on the floor or platform of a station or warehouse while the end 12 is rested 55 on the floor of a car, within the doorway thereof. The loading and unloading trucks are run up and down this gang in transferring the freight to and from the car. This gang is liable to slip causing injury to the 60 operators and damage to the freight. It is the particular object of this invention to provide a novel and improved device which is adapted to be secured to each of the four corners of the gang to prevent this slipping, 65 thereby protecting the operators and the freight.

The attachment for the gang comprises a casting of steel or other hard metal 13, which includes an attaching flange 14 secured to the edge of the gang by rivets 15, and the vertical tubular member 16, the latter portion being disposed outwardly of the edge of the gang. Longitudinally through the member 16 is a bore 17 having a shoulder 70 18 at the upper end which causes a reduction in the bore, as shown at 19. Disposed within this bore is a pin 20 having its lower end protruding from the lower end of the bore and formed with a point 21. Above 75 this point is a shoulder 22, the upper portion of the pin being thus reduced to fit into the upper portion of the bore, while the lower portion fits in the lower, or larger, portion of the bore. A coil spring 23 encircles the reduced portion of the pin and bears with its opposite ends against the shoulder 22 and against the shoulder 18, 80 with the result that the pin is normally forced downwardly so that its point projects 85 through the lower end of the bore for biting engagement in the platform or the floor of the car. Through the upper end of the reduced end of the pin, above the upper end of the member 16, is a pin 24 for holding 90 the pin 16 against complete movement downwardly through the bore of the member 16.

There is one of the devices, above described, secured to each of the corners of the 100 gang, those at one end being secured inwardly of the bend of the downturned end 11.

There is thus provided a novel and improved device which can be attached to any 105 of the metal gang planks now in use, with-

out modifications thereto, and which will effectively prevent slipping of the gang plank.

What is claimed is:

The combination with a metal gang plank, 5 of tubular members mounted on the corners of the gang plank, slideable pointed pins disposed in the tubular members, resilient means within the tubular members and engaging the tubular members and pins for

normally urging the pins outwardly, and 10 means for limiting the outward movement of the pins.

In testimony whereof I affix my signature in the presence of two witnesses.

EDWARD L. MILES.
